METHOD FOR REPRODUCING FILMS
HAVING A GOFFERED BASEJean Leon Vidal, Paris, France, assignor to Keller-Dorian Colorfilm Corporation, New York, N. Y.,
a corporation of DelawareApplication May 1, 1930, Serial No. 449,060
In France May 2, 1929

11 Claims. (Cl. 88—24)

My invention relates particularly to an improvement in the method of reproducing films of goffered base, but relates especially to the production of films of that kind for use in producing motion pictures.

The object of my invention is particularly to provide a method of reproducing films of the above character, like those employed in the Keller-Dorian process, but in which the lines of the recording and reproducing films may be located at any angle whatsoever in the two films.

Previously, in the Keller-Dorian process it was found that the microscopic lines of the embossing of the two films must be either parallel or rectangular. According to the present invention, on the contrary, the said lines may be set at any angle whatsoever.

After reference to French Patents Numbers 566,432, 573,399, 605,875, of the Keller-Dorian Berthon & Company, and the company, La Societe Francaise de Cinematographie et de Photographic Films en couleurs Keller-Dorian, relating to said process, the conditions are shown which necessarily govern the making of copies of films having a goffered base. This is done by projection with the aid of a special objective which is symmetrical in relation to the diaphragm placed in the common focal plane of the two optical parts. Also, the generators of the goffering of the lenticular cylindrical elements must be effectively and practically parallel. Nevertheless, under those conditions a moiré effect is produced and to eliminate said effect recourse is had to the processes described in either the French Patent No. 571,096 of the Keller-Dorian Berthon & Co., or to the patent of the Company, La Societe Francaise de Cinematographie et de Photographic Films en Couleurs Keller-Dorian, filed upon the 9th day of August, 1928, for a method for making the reticulation and the moiré effect disappear in course of projection or reproduction of films with a goffered base. According to those processes the lines of the goffering must be parallel. However, while it is better to take photographs upon a film

which is goffered lengthwise, it is, on the contrary, much more practical to project pictures with a film which is goffered crosswise. The films goffered lengthwise are better in grade as their manufacture is accomplished by means of the methods indicated in the French Patent No. 627,975 and the additional Patent 33,261, belonging to the company, La Societe Francaise de Cinematographie et de Photographic Films en Couleurs Keller-Dorian, and also in Patent No. 637,978 of Audibert, which give perfect cylindri-

cal surfaces. The recording of images with these films is accomplished with definition, exactitude, and clarity of color.

On the other hand, according to French Patent No. 655,732 of the company, La Societe Francaise de Cinematographie et de Photographic Films en Couleurs Keller-Dorian, it has been proven that projection is more satisfactory with films which are goffered crosswise which, since they do not lose their shape, do not give rise to dominant colors which are so undesirable.

According to the present invention, it is possible, among other advantages, to combine the advantages of said two types of film as it is possible to accomplish recording on films embossed lengthwise and projection with films embossed crosswise, and this can be carried out on the general principle of allowing the two types of embossing on the recording and projection films respectively to be at any desired angle.

Furthermore, it is found from the French Patent No. 566,432 already referred to, and the French Patent No. 573,532 of the company, Keller-Dorian Berthon & Co., that the moiré effect can be made to disappear from such films.

While my invention is capable of being carried out in connection with many different types of apparatus, by way of illustration, I have shown only certain forms of apparatus for use therewith in the accompanying drawing, in which

Fig. 1 is a diagrammatic view, partly in perspective, showing a reproducing objective arranged according to patents above referred to but with the path of the rays for films engraved with crossed lines.

Fig. 2 is an elevation of the usual diaphragm used for reproduction of films with parallel goffering.

Fig. 3 is an elevation of a special diaphragm used in connection with the present invention where the goffering on the two films is located at right angles.

Fig. 4 is a similar view of a modified form diaphragm used with oblique goffering.

In the French Patent 646,160 of the company, La Societe Francaise de Cinematographie et de Photographic Films en Couleurs Keller-Dorian, there is set forth the best means of lighting the copying machine for goffered films consisting in the use of a lamp with a sufficiently long filament or in the adoption of an appropriate focal length of the condenser of the lamp in order to provide uniform illumination to the entire diaphragm of the reproducing objective by placing the goffered film in the projection frame of the original film.

In this manner, the diaphragm, such as the diaphragm D will be entirely lighted by a kind of defraction of the rectilinear filament of the lamp across the network of the film. Accordingly, in 5 the present invention the diaphragm illuminated as above is arranged as shown in the drawing, showing the original or recording film F goffered lengthwise, a new film or reproducing film F' goffered crosswise, O O' indicate the reproducing objective, while D indicates a diaphragm such as either of the diaphragms D' or D'' as shown in Figs. 3 and 4 respectively, when carrying out 10 this invention. When using either of the diaphragms such as shown for example in Figs. 3 and 4, and for goffering of any given character, 15 we can consider, by way of an example, three pre-determined zones of color running parallel to the direction in which the embossing extends and corresponding to any three primary colors 20 of the filter screen which selects the colors of the photographic objective, these three primary colors being designated, for example, R, V, and B. This is as shown in Figs. 1 and 2. In Fig. 3 for instance, there are also shown three additional 25 similar bands, r, v and b, which correspond in the same way with the three same primary colors of any given goffering and three others of the same primary colors, R, V and B, corresponding to a goffering which is perpendicular to the goffering used in connection with the colors, r, v, 30 and b. When these two sets of bands of the three primary colors cross, it is noted that there are, for example, three parts A, B and C of the diaphragm not covered by cross hatching which belong at the same time to the two gofferings perpendicular to each other, but that each one of the 35 spaces A, B and C belongs only to a single primary color, that is to say, where

40. r corresponds to R
v corresponds to V
b corresponds to B

Consequently, if we place in the objective O O' 45 a diaphragm with openings cut out of the same corresponding to the spaces A, B and C in the direction of the cut which is indicated by the arrow, we shall be able to reproduce the goffered films 50 in fact, the same result can be obtained where the goffering is located at any angle whatsoever, as for instance, the oblique angle as shown in Fig. 4.

When using such diaphragms, as for instance 55 the diaphragm in Fig. 3 used with right angle goffering, the moiré effect disappears entirely. Furthermore, each sector opened and uniformly lined up as above explained, can be diaphragmed to a greater or lesser degree as found necessary, in order to rectify the colors in accordance with the procedure of the French Patent 60 No. 646,164 already referred to.

While I have described my invention in detail, I wish it to be understood that many changes 65 may be made thereto without departing from the spirit of same.

I claim:

1. The method which comprises producing a picture on a line goffered film from a line goffered 70 film, in which the goffering of one film is located at an angle to the goffering of another, by projecting light on to the first-mentioned film from the last-mentioned film through a diaphragm adapted to transmit the light only to the portions 75 of the goffering of the first-mentioned film where

the like-color producing zones of the gofferings of the two films are in registry.

2. The method which comprises producing a picture on a goffered film from a goffered film, in which the goffering of one film is located at an angle to the goffering of another, by projecting the light onto the first-mentioned film through a diaphragm having openings corresponding to the overlapping colors of like color bands parallel to the goffering of the two films respectively. 80

3. The method which comprises producing a picture on a goffered film from a goffered film, in which the goffering of one film is located at an angle to the goffering of another, the goffering of the last mentioned film being arranged lengthwise thereof, and the goffering of the first mentioned film crosswise thereof, by projecting the light onto the first-mentioned film through a diaphragm having openings corresponding to the overlapping colors of like color bands parallel to the goffering of the two films respectively. 90

4. The method which comprises producing a picture on a goffered film from a goffered film, in which the goffering of one film is located at an angle to the goffering of another, the goffering of one film being arranged obliquely to the goffering of the other film, by projecting the light onto the first mentioned film through a diaphragm having openings corresponding to the overlapping colors of like color bands parallel to the goffering of the two films respectively. 100

5. The method which comprises producing a picture on a line goffered film, with the absence of moiré effects, from a line goffered film, in which the goffering of one film is located at an angle to the goffering of another by projecting light on to the first-mentioned film from the last-mentioned film through a diaphragm adapted to transmit the light only to the portions of the goffering of the first-mentioned film where the like- 110 color producing zones of the gofferings of the two films are in registry. 115

6. The method which comprises producing a picture on a goffered film, with the absence of moiré effects, from a goffered film, in which the goffering of one film is located at an angle to the goffering of another, by projecting the light onto the first-mentioned film through a diaphragm having openings corresponding to the overlapping colors of like color bands parallel to the goffering of the two films respectively. 120

7. The method which comprises producing a picture on a goffered film, with the absence of moiré effects, from a goffered film, in which the goffering of one film is located at an angle to the goffering of another, the goffering of the last mentioned film being arranged lengthwise thereof, and the goffering of the first mentioned film cross-wise thereof, by projecting the light onto the first mentioned film through a diaphragm 130 having openings corresponding to the overlapping colors of like color bands parallel to the goffering of the two films respectively. 125

8. The method which comprises producing a picture on a goffered film, with the absence of moiré effects, from a goffered film, in which the goffering of one film is located at an angle to the goffering of another, the goffering of one film being arranged obliquely to the goffering of the other film, by projecting the light onto the first-mentioned film through a diaphragm having openings corresponding to the overlapping colors of like color bands parallel to the goffering of the two films respectively. 140

9. In the method of making prints from a lin- 145

early lenticular film containing minute color component images that comprises projecting the images upon a sensitive linearly lenticular film by means of an optical system consisting of two complete objectives, the improved steps of placing the films with their lenticulations of one film at an angle to those of the other and projecting images from one film to the other through a diaphragm situated in the plane of the aerial image and having a series of openings diagonal to both sets of lenticulations.

10. The method which comprises producing a picture on a line goffered film from a line goffered film, in which the goffering of one film is located at an angle to the goffering of another, by projecting light on to the first-mentioned film through the last-mentioned film and through a

diaphragm so as to transmit the light substantially onto the portions of the goffering of the first-mentioned film where the like-color producing zones of the gofferings of the two films are in registry.

11. The method which comprises producing a picture on a line goffered film, with the absence of moiré effects, from a line goffered film, in which the goffering of one film is located at an angle to the goffering of another, by projecting light on to the first-mentioned film through the last-mentioned film and through a diaphragm so as to transmit the light substantially only to the portions of the goffering of the first-mentioned film where the like-color producing zones of the gofferings of the two films are in registry.
